FIG. 1

FIG. 2

FIG. 3

FIG. 4

FIG. 1 is a front perspective view taken from one side of a vending machine showing our new design;

FIG. 2 is an elevational view thereof taken from the side shown in FIG. 1, the opposite side being substantially the same;

FIG. 3 is a front perspective view taken from one side of a modified form of the vending machine shown in FIGS. 1 and 2; and

FIG. 4 is an elevational view of the side shown in FIG. 3, the opposite side being essentially the same.

The rear of the vending machine is essentially flat and plain.

The dominant features of our design reside in the portions shown in full lines.

We claim:

The ornamental design for a vending machine, as shown and described.
